UNITED STATES PATENT OFFICE.

SAMUEL DANKS, OF CINCINNATI, OHIO.

IMPROVEMENT IN ROTARY PUDDLING-FURNACES.

Specification forming part of Letters Patent No. 96,206, dated October 26, 1869.

To all whom it may concern:

Be it known that I, SAMUEL DANKS, of Cincinnati, in the county of Hamilton and State of Ohio, have invented certain Improvements in Rotary Puddling-Furnaces, of which the following is a specification:

following is a specification:
My invention consists in the construction and arrangement of series of pipes for the conveyance of water, steam, air, or other suitable cooling substance close to the passages to and from the rotary refining-chamber, and projecting corners and surfaces of puddling-furnaces, and to a water, steam, or air casing surrounding the refining-chamber, for the purpose of reducing the temperature of those parts of the furnace most exposed to intense heat, and also to annular metallic facings attached to the refining-chamber for its protection from excessive heat.

Figure 1 is a longitudinal section of a rotary puddling-furnace having my improvements connected therewith. Fig. 2 is a one-half section and one-half elevation of the fire-bridge, the annular water-collar, and the steam, water, or air casing as seen from the grate. Fig. 3 is a sectional elevation of the shiftable piece K, the section being taken through the annular pipe l.

A represents the rotary refining-chamber of the puddling-furnace. It consists of a cylinder constructed of suitable refractory metal. Its ends are of the form of truncated cones. B B are rollers, arranged beneath the chamber, which they support while permitting its free rotation, accomplished by means of gearing. The bridge C has incased within it a coil of pipes, D, for the conveyance of water, steam, air, or other cooling substance. The first return of the coil of pipes D is carried through the arch over the passage from the grate to the refining-chamber, as shown at J in Fig. 1. This pipe is connected with the spiral pipe F, incased in the annular water, steam, or air collar G, which is secured to the bridge end of the grate a, or about the hot-air passage of which the bridge C forms the lower edge or face. The conically concave face of the annular water, steam, or air collar is of a form adapting it to fit closely the surface of the end of the refining-chamber. A discharge-pipe, H, is connected with the last return of the spiral pipe F in the annular collar G, and

terminates at an opening in or near the top of the water, steam, or air casing I, which is constructed of thin metal, having its edges turned in toward the refining-chamber, which it entirely surrounds without being in immediate contact with it.

ate contact with it. The mouth of the shiftable piece K, which is in immediate contact with the end of the refining-chamber A farthest removed from the grate, is constructed with an annular pipe, l, in the edge thereof, the cooling substance being supplied to it through the feed-pipe v. The inner conical faces of the ends of the rotary refining chamber A are covered with the annular metal facings L, secured in place by bolts or screws. The outside face of the shiftable piece K is protected from the heat by the steam, water, or air chamber k. The edges and faces of the opening from the grate to the rotary refining-chamber over the bridge C, and also the ends of the chamber A and movable section of the smoke-flue, are the parts of the puddling-furnace subjected to the most intense heat, and, consequently, are quickly destroyed.

destroyed.

To prevent the rapid destruction of the exposed parts of the furnace, I have into close proximity with them a series of pipes or confined channels for the conveyance of water, steam, air, or other cooling substance, which flows freely, or may be forced to circulate, through said ducts, that a low temperature may be insured. The current of cooling substance, having passed through the coil in the bridge C, is conveyed by the pipe J over the opening from the grate a to the chamber A, into the spiral pipe F in the annular collar G, reducing the temperature of the parts by and through which it passes, and is emptied from the discharge-pipe H upon the top of the rotary refining-chamber A, over the surface of which it spreads, diminishing its temperature. Finally, the steam or gases evolved from the cooling substance in its passage through the pipes escapes under the edges of the casing I, and the fluid part, sinking to the lowest part of the casing, overflows the same edges and escapes into a suitable receptacle.

A cooling substance, such as water, steam, or air, is introduced into the chamber k , which is constructed upon the outer face of the shiftable piece K farthest removed from the grate;

thence it is conducted by the pipe *l'* into the annular pipe or chamber *l*, located in one edge of the shiftable piece *K*, and in contact with the metallic ring *L*, or, in the absence thereof, with the edge of the refining-chamber *A*. The cooling substance is carried off, after its passage through the ring *l*, by the waste-pipe *l''*, and discharged into the water, steam, or air chamber between the casing *I* and the rotary refining-chamber *A*.

The facings *L* are attached, in a secure manner, either to the interior conical ends of the refining-chamber *A*, or to the exterior thereof, by bolts or screws. The facings may, for convenience in handling, be constructed in sections. They serve as an additional protection to the ends of the refining chamber *A*.

Each end of the rotary refining-chamber *A* may be protected, by an annular collar, *G*, from the action of the heat.

I claim as my invention—

1. The annular water, steam, or air collar *G*, constructed substantially as herein shown and described, for the purpose of preserving a low temperature of one or each of the ends of the rotary refining-chamber of puddling-

furnaces with which the collar is in contact.

2. The water, steam, or air pipe *J*, located in the arch of the passage from the grate *a* to the refining-chamber *A*, substantially as and for the purpose set forth.

3. The water, steam, or air casing *I*, constructed substantially in the manner and for the purpose herein shown and described.

4. The annular water, steam, or air pipe *l*, located in the edge of the shiftable piece *K*, which is in immediate contact with the mouth of the refining-chamber when a heat is on, as and for the purpose specified.

5. The water, steam, or air chamber *k*, located upon the outside face of the shiftable piece *K*, as and for the purpose herein set forth.

6. The annular metallic facings *L*, secured to the conical ends of the rotary refining-chamber *A*, substantially in the manner and for the purpose specified.

SAMUEL DANKS.
